FIG. 1.

FIG. 2.

Cameron, Kerkam & Sutton Attorneys

UNITED STATES PATENT OFFICE

2,194,634

RELAY DEVICE

Paul L. Betz, Baltimore, Md., assignor to Consolidated Gas Electric Light and Power Company of Baltimore, Baltimore, Md., a corporation of Maryland

Application March 29, 1933, Serial No. 198,751

8 Claims. (Cl. 175—115)

This invention relates to relay devices and more particularly to relay devices suitable for use in controlling the operation of a gas burner, although the invention is not restricted to this application.

Devices of this type are described in my prior United States Patent No. 2,087,216 dated July 13, 1937, and in my prior application Serial No. 38,656 filed August 30, 1935. In these prior devices an electric ignition device, such as a coil of wire adapted to be heated to incandescence by the passage of an electric current therethrough, is energized whenever the relay is energized and is connected with the relay in such a manner that the relay will not be energized to turn on the gas unless current flows through the ignition device. These prior devices give very satisfactory results in many cases, but in the control of certain gas burners, the operating life of such a continuously energized ignition device may be too short.

It is an object of the present invention to provide a novel relay device of the type characterized above wherein the circuit arrangement of the relay is such that the ignition device is energized only during a period necessary to ignite the gas burner and is thereafter deenergized until the system has been shut down and the relay is called upon to operate again.

While the invention is not restricted to a construction and arrangement of the type disclosed in my prior patent and application and may be embodied in other suitable constructions, it is another object of the invention to provide a modification of the circuit arrangements of these prior devices such as to provide for the deenergization of the ignition device after the gas burner is ignited while preserving the safety features of said prior devices.

Other objects of the invention will appear more fully hereinafter as the description proceeds.

One embodiment of the invention has been illustrated in the accompanying drawing but it is to be expressly understood that said drawing is for purpose of illustration only and is not to be construed as a definition of the limits of the invention, reference being had to the appended claims for this purpose.

In the drawing:

Fig. 1 is a view in section of a suitable construction for a relay device embodying the invention; and

Fig. 2 is a diagrammatic drawing of a relay circuit embodying the invention.

The devices disclosed in my aforesaid patent and application embody a relay armature which, when the relay is deenergized, occupies a position such that it cannot be actuated by the main relay coil, so that supplementary means such as a bimetallic strip or a supplementary relay coil is needed to

initiate the operation of the relay. By suitably delaying the operation of these supplementary means, a time interval is provided during which the electric ignition device may be heated to ignition temperature before the relay operates to turn on the gas.

For purposes of illustration the invention is described hereinafter with reference to a relay device of this type embodying a supplementary relay coil, but it will be understood that the invention is not restricted to this particular type of device as any other suitable construction may be employed.

Referring now to Fig. 1, the structure of the relay is similar to that described in my prior Patent No. 2,087,216 and comprises a frame consisting of spaced side plates 1 between the ends of which are secured upright supports 2 of any suitable material. Intermediate their ends the side plates 1 are connected by upper and lower plates 3 which provide a means for supporting a tube 4. A solenoid armature 5 is slidable within the tube 4, said armature being suitably secured to an operating rod 6 as by means of a set screw. The movement of the armature and rod is limited in any suitable manner as by the nuts 7 adapted to engage the lower and upper ends of the tube 4.

As stated above the relay device shown herein embodies two solenoid coils both of which must be energized to cause the initial movement of the armature 5 from the position shown in Fig. 1, the main coil being, however, sufficient to retain the armature in operative position. The main relay coil is shown at 8, being wound on the tube 4 and energized by leads 9 and 10, and the supplementary relay coil is shown at 11, this coil being also wound on the tube 4 and energized by leads 12 and 13.

The support 2 at one end of the relay carries two pairs of contacts. One pair of contacts, comprising the contact arms 14 and 15 and the co-operating contacts 16, are closed when the relay is deenergized as shown in Fig. 1. The other pair of contacts, comprising the arms 17 and 18 carrying contacts 19, are open when the relay is deenergized. To this end the arm 18 may be arranged to depress the arm 14 by means of the block 20 to maintain the contacts 16 normally in engagement and the contacts 19 normally open. When the relay is operated, the nut 7 on the upper end of the operating rod 6 engages the forked end 21 of the arm 18 and lifts said arm to bring contacts 19 into engagement, whereupon contact arm 14 rises preferably because of its resilience and separates the contacts 16.

At the other end of the relay a third pair of contact arms 22 and 23 are provided with co-operating contacts 24 which are normally open. These contacts are arranged to be closed after a

predetermined interval following the energization of the relay and to this end the arm 22 may comprise a bimetallic strip surrounded by a heating coil 25.

5 The circuit arrangement of the relay is more clearly shown in FIG. 2. The relay is connected to the circuit at the terminals 26 and 27. The wire 9 leads from terminal 26 to the main relay coil 8 and the wire 16 leads from the other end 10 of the coil 8 by way of a wire 28 to the terminal 27, whereby the coil 8 is connected across terminals 26 and 27 and is energized whenever current is supplied to the relay. The supplementary relay coil 11 is connected across the terminals 26 and 27 by a circuit which includes the normally open contacts 24 to provide the delayed operation of the relay as described above, and which circuit also includes an electric ignition device 33 to prevent operation of the relay unless current 15 flows through the ignition device as explained above. To this end one of the contacts 24 is connected to the wire 9 by a wire 29, the other contact 24 being connected to one end of the coil 11 by the wire 12. The wire 13 leads from the other 20 end of the coil 11 to a wire 30 connected to one of a pair of relay terminals 31 and 32 across which is connected the ignition device 33, the other terminal 32 being connected by a wire 34 with the wire 28 leading to the relay terminal 27. Hence 25 it will be observed that the supplementary coil 11 cannot be energized to initiate the operation of the relay unless its energizing circuit is completed through the ignition device 33 and until the contacts 24 are closed by the heating coil 25 as 30 above described. This arrangement provides the safety features described in connection with the prior devices referred to above in that the relay will not operate to turn on the gas unless the ignition device 33 is in operative condition and furthermore will not operate until after a predetermined interval during which the ignition device 33 may reach ignition temperature.

The circuit of the heating coil 25 is also completed through the ignition device 33, in order 45 that said device may be energized during said predetermined interval and may reach ignition temperature before the relay operates. For this purpose one end of the coil 25 is connected to the wire 9 by means of a wire 35 and the other 50 end is connected to one of the contacts 16 by a wire 36. The other contact 16 is connected to wire 30 by means of wire 37 thereby completing the circuit of the coil 25 by means of wire 30, ignition device 33 and wires 34 and 28.

55 The operation of the relay will be understood from the foregoing description and may be summarized briefly as follows:—When current is supplied to the relay, the main coil 8 is energized through the circuit across the relay terminals 26 and 27 as described above. The relay is not operated, however, inasmuch as the position of the armature 5 is such that the magnetic field of the coil 8 is insufficient to lift the armature. Hence it is necessary to energize the supplementary coil 11 so that its magnetic field may assist the magnetic field of the coil 8 to initiate the operation of the relay. The heating coil 25 is energized, provided that its circuit is completed through the ignition device 33, and after a predetermined interval 60 closes the contacts 24. This completes the circuit of the supplementary coil 11 so that the relay is now operated to close the main relay contacts 19. During the interval required for the coil 25 to reach the necessary operating temperature, the ignition device 33 has also reached

ignition temperature so that when the relay is turned on, the ignition device is in operative condition to ignite the gas.

The circuit arrangement also embodies provision for deenergizing ignition device 33 after it has accomplished its function of igniting the gas as above described. As will be seen, the circuit of the ignition device is completed by two parallel paths, one by way of the contacts 16 and the heating coil 25, and the other by way of the supplementary coil 11 and the contacts 24. The operation of the relay as described above opens the contacts 16, but the ignition device is not immediately deenergized because its circuit is completed through the supplementary coil 11 and contacts 24, this circuit providing a shunt around the open contacts 16. These contacts 24 remain closed until the heating coil 25 cools off to the point where contacts 24 are separated whereupon the ignition device 33 and the supplementary coil 11 are both deenergized. The period during which the ignition device remains energized after the relay operates thus depends on the thermal capacity of the heating elements and may be controlled in the design of these elements.

No change in the position of the armature is caused by these operations because the main coil 8 as stated above is sufficient to maintain the armature in its upper position, and said coil 8 is not affected by contacts 16 or 24. The relay 20 therefore remains in this condition until deenergized whereupon the armature returns to its lower position, opening the contacts 16 and closing the contacts 24. The relay is now ready for another operation.

25 It will be seen that the present invention provides for the combination of the safety features of my prior devices with provision for deenergizing the ignition device after the relay has been operated. This feature is of advantage in the control of gas burners where otherwise the operating life of the ignition device, if continuously energized, would be too short, necessitating frequent servicing and replacement of the energizing device in order to maintain the system in 45 operative condition.

While only one embodiment of the invention has been described and illustrated in the drawing, it is to be expressly understood that the invention is not limited to this embodiment, nor to any particular mechanical construction, as various changes may be made in the form, details of construction and arrangement of the parts without departing from the spirit of the invention. Reference is therefore to be had to the appended claims for a definition of the limits of the invention.

What is claimed is:

1. A relay for controlling the operation of a burner provided with an electric ignition device, said relay comprising relay contacts, an armature for operating said contacts, an electromagnet, said armature occupying a position when the relay is deenergized wherein it cannot be actuated by said electromagnet, means for supplementing the action of said electromagnet to cause initial movement of said armature into the range of actuation by said electromagnet, said means including a control device having time-delayed operation, a relay circuit for energizing said control device including a circuit breaking device operated by said armature and a pair of terminals between which said ignition device may be connected to complete said circuit, the circuit of said ignition device also being completed by a path

in parallel with said circuit breaking device and said path including contacts operated by said control device.

2. A relay for controlling the operation of a burner provided with an electric ignition device, said relay comprising relay contacts, an electromagnet having a movable armature for closing said contacts, said armature occupying a position when the relay is deenergized wherein it can-
5 not be actuated by said electromagnet, supplementary means for causing initial movement of said armature into the range of actuation by said electromagnet, a relay circuit for said sup-
10 plimentary means including a pair of contacts and a pair of terminals between which said ignition device may be connected to complete said circuit, means having time-delayed operation for closing said contacts after the relay has been energized to cause operation of the relay and for
15 opening said contacts after the relay has operated, and an energizing circuit for said last-named means in parallel with said pair of contacts and in series with said pair of terminals and said ignition device.

25 3. A relay for controlling the operation of a burner provided with an electric ignition device, said relay comprising relay contacts, an electromagnet having an armature for closing said contacts, said armature occupying a position when
30 they relay is deenergized in which it cannot be actuated by the field of said electromagnet, means operative in response to temperature changes to cause initial movement of said armature into the range of actuation by said elec-
35 tromagnet, an electric heating element for said means, a relay circuit for said heating element comprising a pair of contacts adapted to be opened by movement of said armature, a relay circuit including a pair of contacts closed on
40 heating said element and opened when said element cools off, and a pair of terminals between which said ignition device may be connected, said circuits being in parallel with each other and in series with said pair of terminals and said igni-
45 nation device.

4. A relay for controlling the operation of a burner provided with an electric ignition device, said relay comprising relay contacts, an armature for operating said contacts, an electromagnet, said armature occupying a position when the relay is deenergized wherein it cannot be actuated by said electromagnet, supplementary means to cause initial movement of said armature into the range of actuation thereof by said elec-
50 tromagnet, a circuit for said supplementary means including a pair of terminals between which said ignition device may be connected and a pair of contacts, temperature responsive means for closing said last named contacts after the relay has been energized and for opening said last named contacts after the relay has been operated, and a heating circuit for said temperature responsive means in parallel with said pair of contacts and in series with said pair of terminals and said igni-
55 nation device, said heating circuit comprising contacts opened by said armature on actuation thereof.

5. A relay for controlling the operation of a burner provided with an electric ignition device, said relay comprising a pair of contacts, an armature for operating said contacts, an electromagnet, said armature occupying a position

when the relay is deenergized wherein it can-
not be actuated by said electromagnet, supple-
10 mentary means to cause initial movement of said armature into the range of actuation thereof by said electromagnet, a circuit for said sup-
15 plimentary means including a pair of terminals be-
tween which said ignition device may be con-
nected and a pair of contacts, an electrically
heated temperature responsive means in series
with said pair of terminals and said ignition de-
vice for closing said last named contacts after the
20 relay is energized, the circuit of said heating
means including a circuit breaking means oper-
ated by said relay to deenergize said heating
means whereby said last named contacts open
25 when the heating means cools off and said igni-
tion device is thereby deenergized.

6. A relay for controlling the operation of a burner provided with an electric ignition device said relay comprising main relay contacts, a 20 main relay coil, an armature, a supplementary relay coil for causing initial movement of the armature when the relay is energized, a circuit for said supplementary coil including a pair of normally open contacts and a pair of relay ter-
25 minals between which said ignition device may be connected to complete said circuit, tempera-
ture responsive means having a heating circuit in parallel with said first circuit and in series with said pair of terminals and said ignition de-
30 vice whereby said means is heated on energiza-
tion of said relay to close said pair of contacts, said second circuit including a circuit breaking means operated by said relay to deenergize said temperature responsive means whereby said tem-
35 perature responsive means cools off and said last named pair of contacts are opened to deenergize said ignition device.

7. A relay for controlling the operation of a burner provided with an electric ignition device, 40 said relay comprising a pair of terminals, a main relay circuit including a relay coil and connected across said terminals, a second relay circuit connected across said terminals and including in series a second pair of terminals between which said ignition device may be connected, said sec-
45 ond circuit having two parallel branches, one of said branches comprising a supplementary relay coil for causing initial operation of the relay and a pair of normally open contacts, and the other branch comprising temperature responsive means for operating said normally open pair of contacts and a second pair of normally closed contacts opened by final operation of said relay.

8. Apparatus for controlling and igniting a gas burner comprising in combination a relay hav-
ing an armature, and relay contacts operated thereby, a relay coil, an electric ignition device for said burner, a relay circuit for energizing said device having parallel branches one of which is 50 normally closed and the other normally open, a supplementary relay coil in said normally open branch for causing initial movement of said armature, temperature responsive means heated by said normally closed branch for making and breaking the circuit through said normally open branch, and means operated by said armature for breaking the circuit through said normally closed branch when said armature moves to its attracted position.
